UNITED STATES PATENT OFFICE.

EMMA HERNHUTER, OF NEW YORK, N. Y.

BAG.

1,157,388.

Specification of Letters Patent.

Patented Oct. 19, 1915.

Application filed December 11, 1914. Serial No. 876,708.

To all whom it may concern:

Be it known that I, EMMA HERNHUTER, a citizen of the United States, residing at New York, in the county of Bronx and State of New York, have invented certain new and useful Improvements in Bags, of which the following is a full, clear, and exact description.

This invention relates to bags or containers, and has for its object to provide a device of this kind with a simple, durable and effective closure which will securely hold the bag closed when desired and which will not interfere with filling the bag when open.

15 A further object is to provide a combined closure or retaining device and handle for carrying the bag in either open or closed position.

20 Other objects will appear as the description proceeds.

The invention will be first hereinafter described in connection with the accompanying drawings which constitute a part of this specification, and then more specifically defined in the claims at the end of the description.

In the accompanying drawings, wherein similar reference characters are used to designate corresponding parts throughout the several views: Figure 1 is a perspective view of a bag constructed in accordance with my invention, the same being shown in closed position. Fig. 2 is a perspective view 35 showing the bag in open position, and Fig. 3 is a similar view of a slightly modified construction.

The bag A is preferably made of paper, and its open upper end is adapted to be 40 closed by an overlapping flap B made integral with and forming a continuation of the blank from which the bag is formed. Just below the flap on the inside of the bag there is secured a reinforcing or stiffening strip C through which and the portion of the bag to which is secured, spaced perforations c are formed for the passage of an endless cord or tape D. The strip C is preferably pasted to the inner surface of the 45 bag in the position illustrated in Fig. 2, but it may be secured in any other suitable manner. The endless cord D is also passed through perforations b arranged in the flap B opposite the perforations c when the flap 50 is folded down into closed position. On the front of the bag, just below the lower edge

of the flap so as not to be covered thereby when the latter is in closed position, a button E is secured, the same being preferably provided with a paper or fiber head or washer below which the cord D may be caught and clamped. When the bag is closed, as illustrated in Fig. 1, the portion of the cord D on the front of the bag is caught under the button E so as to make the said portion of the cord on the front of the bag assume the shape of a V, said button being arranged about equidistant from the two perforations b through which the cord is passed. The portion of the cord on the rear face of the bag is then used as a handle 60 for carrying the container. It will be noted that the weight of the bag and its contents will tend to more firmly hold the cord in engagement with the button E, while the V-shaped portions of the cord extending from said button to the perforations b on the front of the bag will overlap the edge of the flap and effectually retain the same in closed position. When the bag is to be opened, 65 the portion of the cord on the front face thereof is disengaged from the button E, whereupon the flap may be turned upward to the position illustrated in Fig. 2. The portion of the cord which was engaged with the button E when the bag was closed may then be used as a handle for supporting the 70 bag while it is being filled.

If desired, eyelets c' may be placed in the perforations in the reinforcing strip C, 75 as illustrated in Fig. 3. These eyelets not only serve to reinforce the perforations, thereby avoiding the danger of the same being torn, but also constitute an additional means of securing the reinforcing strip C to 80 the bag.

Having thus described my invention what I claim as new and desire to secure by Letters Patent of the United States:—

1. A bag having a closure flap with perforations therein, there being registering perforations in the rear portion of the bag, a button on the front of the bag below the edge of the flap so as not to be covered thereby when closed, and a combined handle and closing device consisting of an endless cord passed through said perforations and adapted to have the portion thereof which is arranged on the front of the bag overlap the edge of the flap and caught under said button while the portion of said cord at the rear of the bag serves as a handle. 100

2. A bag having a closure flap with perforations therein, there being registering perforations in the rear portion of the bag, a button on the front of the bag below the edge of the flap so as not to be covered thereby when closed and substantially equidistant from the perforations in the flap, and a combined handle and closing device consisting of an endless cord passed through said perforations and adapted to have the portion thereof which is arranged on the front of the bag overlap the edge of the flap and

caught under said button while the portion of said cord at the rear of the bag serves as a handle, the portion of the cord in front of the bag being then arranged in the form of a V substantially as described. 15

In testimony whereof I have signed my name to this specification in the presence of two attesting witnesses.

EMMA HERNHUTER.
